UNITED STATES PATENT OFFICE

148,828

DESIGN FOR A PORTABLE AUTOMATIC IRONER

John Tjaarda, Detroit, Mich., assignor to The Sparks-Withington Company, Jackson, Mich., a corporation of Ohio

Application March 8, 1946, Serial No. 127,264

Term of patent 14 years

(Cl. D49—6)

To all whom it may concern:

Be it known that I, John Tjaarda, a citizen of the United States, residing at Detroit, in the county of Wayne and State of Michigan, have invented a new, original, and ornamental Design for Portable Automatic Ironers of which the following is a specification, reference being had to the accompanying drawing, forming part thereof. In the drawing,

Fig. 1 is a perspective view taken from the rear of the ironer embodying my new invention,

Fig. 2 is a perspective view taken from the front of the ironer, and

Fig. 3 is a perspective view taken from the end of the ironer.

I claim:
The ornamental design for a portable automatic ironer, substantially as shown.

JOHN TJAARDA.
